UNITED STATES PATENT OFFICE.

GAILLARD E. WEAVER, OF SPRINGFIELD, ILLINOIS, ASSIGNOR TO WEAVER MANUFACTURING COMPANY, OF SPRINGFIELD, ILLINOIS, A CORPORATION OF ILLINOIS.

TRUCK JACK.

Application filed September 8, 1925. Serial No. 54,855.

The main or leading object of the present invention is the production of a lifting-jack, preferably of the truck style, in which the seat or saddle which carries the load may 5 be caused to descend to an unusually low position and may be raised or elevated to a comparatively great height, whereby the structure is well adapted for use in connection with vehicles fitted with balloon tires of 10 relatively large cross-section.

An added purpose of the invention is the provision of an appliance having the structural and functional characteristics noted which is composed of relatively few mechanical elements, which is effective in action, which can be manufactured at comparatively low cost, and which is not likely 15 to become injured or damaged in ordinary service.

20 A further aim of the invention is to supply a jack of this character in which the load-engaging element may be easily and quickly preliminarily raised to assume the load, preferably by merely pressing on a 25 part of the appliance with the foot, after which the load may be lifted by the cooperating elements provided for that purpose to secure an effective mechanical advantage.

For a full understanding of the invention, reference should be had to the accompanying drawing forming a part of this specification and throughout the several views of which like reference numerals have 35 been used to denote the same parts; this drawing illustrating a present preferred embodiment of the invention, the latter, however, being susceptible of several other embodiments.

In such drawing:—

40 Figure 1 is a side elevation of the new truck-jack with its load-elevating saddle in lowered position;

Figure 2 is a longitudinal section illustrating the parts with such saddle in raised 45 position and showing spring 64 partially omitted for clearness of illustration of other elements; and

Figure 3 is a plan view of the structure with certain elements cut away to more 50 clearly show the details of construction.

Referring to these drawings, it will be perceived that the new and improved truck-jack includes a main, horizontal frame composed of two, rearwardly-diverging, side-

bars 11 and 12 connected together at their 55 front ends by a cross-bar 13 and similarly joined together, about their mid-length, by another cross-bar 14, other elements of the construction, as will be noted hereinafter, co-operating to hold the pair of bars in proper 60 spaced relation.

This main-frame at its back end is supported on a caster-wheel 15 revolvably mounted in a suitable bracket 16 swiveled at 17 on the cross-bar 13.

65 At its forward end, the truck-frame is equipped with a pair of carrying-wheels 18, 18 rotatable on an axle 19, which, between the bars 11 and 12, is equipped with a sleeve 21 acting to hold the side-bars properly 70 separated at this point.

75 A curved or concave saddle or seat 22, adapted to engage and elevate or lower the load, as for example, the axle of an automobile, is fixedly mounted on the front end of a two-bar or duplex, bent lever 23, 23 fulcrumed near the rear end of the appliance on a stationary cross-shaft 24 with spacing sleeves or collars 25, 25 interposed on the shaft between the inner faces of the frame 80 bars 11 and 12 and the outer surfaces of the two companion lever-bars 23, 23.

Near the elbow or bend of the lever 23, 23, it is connected by a pair of links 26, 26 to a short extension 27 of a segmental 85 ratchet 28, rockingly mounted at its center or axis on a fixed cross-shaft 29, midway between the frame side-bars 11 and 12 and in register with the gap between the spaced lever-elements 23, 23, so that, in the lowered 90 position of the lever and its saddle, the ratchet is accommodated in part in this space of the lever.

The shaft 29 is supported in apertures or bearings in a pair of blocks or plates 31, 31 95 mounted against the inner surfaces of the frame side-bars 11 and 12 by means of suitable bolts 32, 32.

To maintain the ratchet-segment midway between the frame-bars the shaft 29 is 100 equipped with spacing sleeves or collars 33, 33 between the opposite faces of the part 28 and the inner surfaces of the supporting elements 31, 31.

105 It will be readily understood, that, by turning the ratchet-member, the lever and its saddle may be raised or lowered as occasion requires, and, to effect the performance of

these functions, the following specified co-operating instrumentalities have been provided.

A long push bar 34 has a tooth 35 designed to cooperate with the teeth of the rockable ratchet-element, such bar being held up to its work by a coiled, contractile spring 36 connected to a lug on its top and to an ear or pin on the cross-bar 14, all as is clearly shown in Figure 2, the bar being guided in its comparatively-slight vertical movements by a pair of guide-fingers 37, 37 overlapping its opposite side faces.

The back, upwardly-bent end of this toothed bar 34 is pivotally connected at 38 to very short, spaced arms 39, 39 of a double, bell-crank operating-handle, composed of two separated members 41, 41 straddling the end of the bar 34 and fulcrumed at 42 on a cross-shaft mounted in the main-frame of the truck and provided with suitable, spacing sleeves 43, 43 between the two bars of which the handle 41 is composed and between them and the frame side-bars 11 and 12.

At its upper end, this handle 41, 41 is supplied with a cross handle-piece or rod 44 adapted to be grasped by the operator in the manipulation of the handle-lever, the latter normally assuming a substantially-upright position, as indicated in Figure 2, by reason of an elevating, coil, contractile spring 45 connected thereto at 46 and to the main-frame at 47.

The upward rocking movement of such operating-handle which is employed not only to actuate the ratchet-segment but also to pull the truck around to different positions on the floor, is limited or restricted by a yoke-abutment 48, fastening in any approved manner, as by welding, to the frame-members 11 and 12.

As will be readily understood, the tooth or dog 35, reciprocated by reason of the vertical, oscillatory movements of the handle 41, is provided for the purpose of turning the ratchet-member in the direction to elevate the saddle and its load; but, of course, the structure requires a holding dog or tooth to maintain the parts in position while the elevating pawl or dog is being shifted to engage a new tooth of the rotary ratchet-member.

This spring-pulled locking dog 51 is rockingly mounted on another cross-shaft 52 in the main-frame, and, similarly supported on the same shaft, there is a dog or pawl controlling member 53 of the shape depicted in Figure 2, a cam slot and pin connection 54 being supplied between the bar 34 and the part 53, and another shorter slot and pin connection 55 being used between the element 53 and the locking dog or pawl.

As is clearly shown, the member 53 has an offset, apertured section 56 through the hole of which a rod 57 extends, such rod being

pivotedly connected at its other end to an arm 58 fulcrumed at 59 on the frame part 12, the arm having a laterally-extended knob or handle 61 and an extension or foot 62, adapted, in the positions of the parts shown in Figure 1, to engage a stop-pin 63 projecting from the outer face of the bar 12, thus limiting the movements of the parts 57 and 58 in this direction, their limit of travel in the opposite direction being determined by the engagement of the rod 57 with the top surface of the frame-bar 12.

A coiled, contractile spring 64 connects the rod at point 65, where an end of the spring extends through a hole in the rod, to an apertured ear 66 forming part of the element 53, whereby the spring when relaxed permits the cooperating members to occupy the positions shown in Figure 1 but being capable of extension and pulling action when the arm 58 is swung down to the left.

To permit the operator to quickly raise the double lever 23, so that its saddle may initially engage the load, rather than be required to operate the step by step ratchet action, an extension-bar 67, projecting between the parallel elements of the handle 41, is bolted at 68, 68 to and between the lever members 23, 23.

By merely depressing the other or forwardly-protruding end of this extension-member 67 with the foot, the lever 23 and its saddle are quickly raised with ease and the ratchet-member is simultaneously turned, the dogs or pawls idly riding over the ratchet-teeth.

The appliance as described operates substantially as follows; it being noted that the saddle in its lowermost location occupies a position below the tops of the adjacent truck carrying-wheels 18, 18, thus permitting this load-lifting element to be introduced beneath a load of only a slight height.

Thereupon, the operator depresses the extension 67 with his foot until the saddle or seat is raised sufficiently to engage under the load, and then, with the pawl-controlling arm 58 in the position shown in Figure 1 with the spring 64 slack, the operator pumps or rocks the handle 41—44 up and down to complete the load-lifting operation.

When the governing arm 58 is in the position indicated, the spring 64 is relaxed sufficiently so that it has no pulling effect on the plate 53, and the holding dog or pawl 51 is free to respond to the action of its lifting spring 50.

Every time that the lever-handle is rocked down, the bar 34 travels lengthwise and its pawl 35 by engagement with the teeth of the ratchet-member turns the latter a predetermined amount corresponding to the distance between two or more teeth, and, as the ratchet-element thus rocks, the ratchet-teeth ride under the holding-dog, the latter oscil-

lating slightly as required and responding to the action of its spring 50, whereby it holds the load elevated when the lifting-dog is retracted during the upward movement of the handle to engage a new ratchet-tooth, and thus it will be perceived that a heavy load may be raised a little at a time by merely rocking or pumping the handle 41, and without undue or excessive effort on the part of the workman.

During such actuation of the co-operating instrumentalities, when the push bar 34 travels towards the ratchet-element, its pin of the pin-and-slot connection 54 rocks the part 53 downwardly, because the dog 35 is moved in that direction by the ratchet-element itself, but, owing to the loose connection with the locking-pawl 51, the latter is not rendered inoperative.

When it is desired to lower the load step by step, the arm 58 is swung to the left, as the parts are viewed in Figure 1, by the operator's foot engaging knob 61 until a portion of the rod 57 rests on the top of the frame part 12, thus limiting the turning movement of the element 58.

When such arm is in the position referred to, the spring 64 is extended or elongated sufficiently to be more powerful than the holding-dog spring 50, and, also, this spring is strong enough to rock the plate 53 downwardly, and, in doing so, it removes the lifting-dog from engagement with the corresponding ratchet-tooth, the pin of the bar 34 being in the left-hand portion of its slot in the plate 53.

Therefore, when the handle 41 is rocked down, the lifting-dog engages the next tooth and slightly lifts the load, whereupon, the holding-dog is automatically disengaged from its tooth, owing to the fact that the spring 63 is stronger than the spring 50 and the holding-dog pin is in the upper end of its slot in plate 53.

Then, while the handle 41 is permitted to rise, thus lowering the load, the pin on bar 34 engages the top margin of its slot in the plate 53 and rocks the plate downwardly sufficiently so as to relieve the locking-dog of the action of spring 64 and the former, responding to the pull of its spring 50, engages the ratchet-member and holds the load in the lower position until the lifting-dog is again operated to lower the load the next step, whereupon the holding-dog repeats the specified operation.

Those trained in this line of work will readily understand that the several stated and other objects and aims of the invention are accomplished in the new structure as illustrated and described, but that the invention is not limited to this particular embodiment thereof and that many minor mechanical changes may be incorporated therein without departure from the fundamental

principles involved and without the loss of any of the attendant material advantages accruing therefrom.

I claim:

1. In a truck-jack, the combination of a truck-frame, carrying-wheels therefor, a load lifting and lowering lever fulcrumed on said frame and having an extension beyond the fulcrum on that side of the latter opposite the place where the lever assumes the load, a ratchet-member rockingly mounted on said frame, an operative connection between said ratchet-member and lever, an operating-handle fulcrumed on said frame, and means enabling said handle to operate said ratchet-member step by step including pawls coacting with the latter, whereby the operator by means of said extension may quickly rock said lever upwardly to approach the load initially without rocking the handle.

2. In a truck-jack, the combination of a truck-frame, carrying-wheels therefor, a recessed load lifting and lowering lever fulcrumed on said frame, a ratchet-member rockingly mounted on said frame and adapted to extend into said lever recess when the lever is in its lowermost position, an operative connection between said ratchet-member and lever, and means to actuate said lever step by step including an operating-handle and pawls coacting with said ratchet-member.

3. In a truck-jack, the combination of a truck-frame, carrying-wheels therefor, a load lifting and lowering lever fulcrumed on and near one end of said frame and adapted to engage the load near the opposite end of the frame, a ratchet-member rockingly mounted on said frame near such opposite end, a link connecting said ratchet-member and lever, an operating-handle fulcrumed on said frame near that end thereof having said lever fulcrum, means whereby said handle may operate said ratchet-member including operating and holding pawls, and a pawl-controlling member operable with the workman's foot at the handle-equipped end of the frame.

4. In a truck-jack, the combination of a truck-frame, carrying-wheels therefor, a load lifting and lowering lever fulcrumed on said frame and having an extension thereon above said fulcrum and projecting beyond the fulcrum on the side opposite where the lever engages the load, a ratchet-member rockingly mounted on said frame, a link connecting said ratchet-member and lever, a vertically rockable handle fulcrumed on said frame, means whereby the movements of said handle actuate said ratchet-member and lever step by step including operating and holding pawls cooperating with the former, and means for controlling the action of said pawls on the ratchet-member, pres-

sure on said extension by the operator causing the lever to rise initially quickly under the load without resorting to the step by step action of the ratchet-member.

5. In a truck-jack, the combination of a truck-frame, carrying-wheels therefor, a lever fulcrumed on said truck-frame near one end thereof, a saddle on said lever adapted to raise and lower the load, a ratchet-sector rockingly mounted on and near the opposite end of said truck-frame, a link hinged directly to said ratchet-sector and

lever near said saddle, means to rock said ratchet-sector including a handle fulcrumed on said truck-frame near the fulcrum of said lever and pawls coacting with said ratchet-sector, and means adjacent the handle end of said truck-frame permitting the operator to initially rock said lever to cause its saddle to approach the load without resorting to movement of said handle. 15 20

In witness whereof I have hereunto set my hand.

GAILARD E. WEAVER.
